COMBINED TOY WAGON AND TRAILER

Mortier W. La Fever, Jr., New Orleans, La.

Application April 26, 1949, Serial No. 2,256

Term of patent 7 years

(Cl. D34—15)

To all whom it may concern:

Be it known that I, Mortier W. La Fever, Jr., a citizen of the United States, residing at New Orleans, in the parish of Orleans and State of Louisiana, have invented a new, original, and ornamental Design for Combined Toy Wagon and Trailer, of which the following is a specification, reference being had to the accompanying drawing, forming part thereof.

Fig. 1 is a perspective view of a combined toy wagon and trailer, showing my new design;

Fig. 2 is a top plan view thereof; and

Fig. 3 is a sectional view taken along line 3—3 in Fig. 2.

The characteristic features of my design are shown in full lines in the drawing.

I claim:

The ornamental design for a combined toy wagon and trailer, as shown and described.

MORTIER W. LA FEVER, JR.
